US00D686043S

(12) **United States Design Patent**
Del Solar et al.

(10) **Patent No.:** **US D686,043 S**
(45) **Date of Patent:** **** Jul. 16, 2013**

(54) **CONTAINER**

(71) Applicant: **Playtex Products, LLC**, Shelton, CT (US)

(72) Inventors: **Maria Alexandra Del Solar**, Stamford, CT (US); **Diana Sierra**, North Bergen, NJ (US)

(73) Assignee: **Playtex Products, LLC**, Shelton, CT (US)

(**) Term: **14 Years**

(21) Appl. No.: **29/439,403**

(22) Filed: **Dec. 11, 2012**

Related U.S. Application Data

(62) Division of application No. 29/389,731, filed on Apr. 15, 2011, now Pat. No. Des. 675,067.

(51) **LOC (9) Cl.** **07-07**

(52) **U.S. Cl.** **USPC** **D7/629**

(58) **Field of Classification Search**

USPC D7/628-630, 510, 511, 536, 538-542; D9/516, 530, 539; 220/203.18, 303, 714, 220/731, 736, 212, 229, 375, 837, 780-806, 220/675, 574-575

See application file for complete search history.

(57) **CLAIM**

The ornamental design for the container, as shown and described.

DESCRIPTION

FIG. 1 is a perspective view of the container according to an exemplary embodiment of the present disclosure; FIG. 2 is a front view of the container of FIG. 1;

FIG. 3 is a back view of the container of FIG. 1;

FIG. 4 is a left-side view of the container of FIG. 1;

FIG. 5 is a right-side view of the container of FIG. 1;

FIG. 6 is a top view of the container of FIG. 1; and,

FIG. 7 is a bottom view of the container of FIG. 1.

The broken lines in the drawings illustrating environmental structure or boundaries that form no part of the claimed design.

1 Claim, 7 Drawing Sheets
